United States Patent Office

Des. 203,401
Patented Jan. 4, 1966

203,401

KALEIDOSCOPE

John L. Burnside III, 2517 Outpost Drive,
Los Angeles, Calif.

Filed Nov. 2, 1964, Ser. No. 82,438

Term of patent 14 years

(Cl. D34—15)

Fig. 8

Fig. 9

FIGURE 1 is a perspective view of a kaleidoscope, embodying my new design;

FIGURE 2 is a side elevational view of the kaleidoscope, as seen from the rear of FIGURE 1;

FIGURE 3 is a left end elevational view of the kaleidoscope, shown in FIGURE 1;

FIGURE 4 is a right end elevational view of the kaleidoscope, shown in FIGURE 1;

FIGURE 5 is a sectional view of the kaleidoscope taken along the line 5-5 in FIGURE 1;

FIGURE 6 is a perspective view of another embodiment of a kaleidoscope, employing my new design;

FIGURE 7 is a side elevational view of the kaleidoscope, as seen from the rear of FIGURE 6;

FIGURE 8 is a left end elevational view of the kaleidoscope, shown in FIGURE 6;

FIGURE 9 is a right end elevational view of the kaleidoscope, shown in FIGURE 6;

FIGURE 10 is a sectional view of the kaleidoscope taken along the line 10-10 in FIGURE 6;

FIGURE 11 is a perspective view of still another embodiment of a kaleidoscope, employing my new design;

FIGURE 12 is a side elevational view of the kaleidoscope, as seen from the rear of FIGURE 11;

FIGURE 13 is a right end elevational view of the kaleidoscope, shown in FIGURE 11;

FIGURE 14 is a left end elevational view of the kaleidoscope, shown in FIGURE 11; and

FIGURE 15 is a sectional view of the kaleidoscope taken along the line 15-15 in FIGURE 11.

I claim:

The ornamental design for a kaleidoscope, as shown and described.
